STORAGE AND DISPENSING APPARATUS
FOR LIQUEFIED GASESLoyd J. White, San Antonio, Tex., assignor to
Southern Steel Company, a corporation of
Texas

Application September 26, 1935, Serial No. 42,337

5 Claims. (Cl. 62—122)

This invention relates to storage and dispensing apparatus for liquefied gases and, among other objects, aims to provide an improved compact and relatively simple installation adapted 5 to be assembled at the factory and shipped as a complete unit ready to be connected for use in a household. The main idea is to provide means to protect the dispensing and controlling apparatus located on the outside of the storage tank 10 from destructive vibration in transit and when the plant is installed underground to protect the mechanism from the surrounding earth fill, from unauthorized tampering and from dust, rain and extreme cold.

15 Other aims and advantages of the invention will appear in the specification, when considered in connection with the accompanying drawings, wherein:

Fig. 1 is a vertical longitudinal sectional view 20 of an installation embodying the invention;

Fig. 2 is a sectional view taken on the line 2—2 of Fig. 1; and

Fig. 3 is a sectional view taken on the line 3—3 25 of Fig. 1.

Referring particularly to the drawings, the installation there shown for illustrative purposes is designed for use in dispensing liquefied petroleum gases, such as normal butane, isobutane, propane or a mixture of butane and propane 30 gases and the apparatus is adapted to be buried in the ground. In this instance, the liquefied gas is stored in a horizontally arranged cylindrical tank 10 of any suitable capacity. This tank is adapted to be filled with liquefied gas under pressure

35 through a stand pipe 11 and a branch 12 having an ordinary inlet valve 13. As the liquefied gas is being charged into the tank, vaporized gas in the tank is allowed to escape into the air or into the filling tank through a pipe 14 having an outlet valve 15, to make room for the new 40 supply of liquefied gas. The lower end of pipe 14 determines the level to which the liquefied gas can be raised. Some clearance or vapor space is required for safe operation.

45 The stand pipe 11 conveniently carries a level gage 16 at its upper end connected to an ordinary float 17 within the tank, although, it is to be understood that any other convenient type of level indicating apparatus may be employed.

50 The vapor under pressure is delivered through a conduit 18, having a hand valve 19; thence, through an ordinary pressure reducing regulator 20 to an outlet pipe 21 and a service main 22. In this instance, water is conducted through the 55 liquefied gas in the tank to insure that it is al-

ways heated to the vaporization temperature, notwithstanding the outside temperature or temperature of the surrounding earth.

Herein, the domestic water supply is connected by a pipe 23 to a cylindrical conduit 24 extending vertically into the tank to its bottom from the outside. This conduit is shown as being closed at both ends. The water enters near the top and is discharged from the bottom through a vent pipe 25 in heat exchanging relation with the liquefied gas and conveniently passes through one end of the tank, as shown. Thus, circulation of the water supplies ample heat to vaporize the liquid.

The circulating water is also used in this instance to re-vaporize any condensed gas in the service outlet conduit. For this purpose, the outlet pipe 21 extends into the cylindrical conduit 24 to a point near the bottom thereof, the lower end being closed and preferably supported by a cross bar or bracket 26.

The service pipe 22 extends through the wall of the conduit 24 near its upper end and is connected to the pipe 21 therein, thus providing a vertical trap to catch any condensed gas vapor. 25 This condensate is quickly re-vaporized by the circulating water in the cylindrical conduit. This is a very important feature, especially in plants used in extremely cold climates because the gas vapor condenses at a temperature between about 30 48° F. and 32° F., depending on the mixture employed. Hence, the water which is always above the freezing point will supply sufficient heat to re-vaporize the liquefied gas.

As is usual in systems of this type, an ordinary 35 relief valve 27 is connected to the low pressure side of the regulating valve 20 to protect the appliances from any excessive pressure. This relief valve has an outlet conduit 28 and a vent pipe 29. Also, a vent pipe 30 is connected to the 40 pressure regulator. All of these pipes are shown as extending above the ground level so that no water can submerge them and interfere with their functions.

To protect the mechanism outside the tank 45 during shipment and after its installation in the ground, there is shown a sheet metal casing 31 which can be of any suitable shape but is preferably frusto-pyramidal, having four sides converging upwardly. The lower ends are cut to 50 conform to the contour of the tank and opposite side walls are preferably bolted to angle brackets 32 welded on the tank. The top of the casing or housing is closed by a suitable cover 33 hinged or otherwise removably secured thereto. It is 55

shown as having a pipe handle 34 providing a vent for the interior of the casing. Incidentally, the pipes 28, 29, and 30 are shown as being secured near their upper ends to one wall of the housing. It will be observed that the upper end of the housing 31 protrudes slightly above the ground so that the apparatus within is readily accessible by removing the cover.

It is important that the pressure regulator be protected from freezing temperatures in order that it may function properly. In mild climates the casing alone is sufficient for this purpose. In cold climates the interior of the casing is preferably filled or lined with any suitable heat insulating material, such as asbestos or rock wool. In Fig. 1, the casing has a layer 35 of such lining which is preferably a few inches thick. It retards the escape of the earth's heat through the top of the casing. It will be understood that the earth's heat is used to help vaporize the liquefied gas in the tank. In some instances the casing will be filled with such insulation to a point above the level of the regulator 20 better to protect the apparatus in cold weather.

Thus, it will be clear that the apparatus is well protected. The whole unit may be assembled and tested at the factory and the casing will serve to prevent damage to the parts during shipment. Otherwise, the pipes might be knocked or jarred and cause dangerous leaks. Moreover, the casing makes all of the apparatus easily accessible for service, inspection and repairs. Also, the complete units may be displayed in sales rooms and present an attractive appearance.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. In a liquefied gas storage and dispensing plant of the class described, a storage tank; dispensing devices, including a pressure reducing regulator connected to said tank; a service pipe connected to said regulator; and heat exchanging means associated with said service pipe to re-vaporize any condensed gas therein.
- 50 2. In a liquefied gas storage and dispensing

plant of the class described, a storage tank; dispensing means connected to the tank for delivering gas at a low pressure therefrom; a service pipe leading from said dispensing means having a portion projecting into said tank; a water conduit around said pipe within the tank providing a heat exchanger for re-vaporizing condensed gas therein; and water pipes connected to said conduit for circulating water in heat exchanging relation to liquefied gas in the tank. 10

3. A storage and dispensing system for liquefied petroleum gases under pressure comprising, in combination, a storage tank adapted to be buried in the ground; a valved filling conduit for the storage tank; a valved gas dispensing conduit connected to the tank; an automatic pressure regulator connected to the dispensing conduit; a protecting casing secured to the tank and providing a housing for said filling conduit, said valve and said pressure regulator; a safety vent pipe connected to said pressure regulator and projecting upwardly into said protecting casing to a point near the top; and a vented removable cover for said casing adapted to project above the ground so that the parts in said 25 casing are accessible for removal or repairs.

4. In a liquefied gas storage and dispensing system of the class described, a storage tank for holding liquefied gas under pressure; dispensing means, including a pressure reducing valve connected to said tank; and a heat exchanger connected to the dispensing means to re-vaporize any condensate in the dispensing conduit after the gas passes through said pressure reducing valve. 35

5. In a liquefied gas storage and dispensing plant of the character described, a storage tank for holding the liquefied gas under pressure adapted to be buried in the ground; filling and dispensing devices, including a pressure regulator and valved conduits secured to the tank and projecting upwardly therefrom; a protecting casing for said devices secured to the tank adapted to be partially buried in the ground with the tank; 45 a vent for said regulator extending to the top of the casing above the ground level; and a removable cover for said casing to permit access to said devices.
